UNITED STATES PATENT OFFICE.

LEWIS F. FALES, OF WALPOLE, MASSACHUSETTS.

SEWING MACHINE.

Application filed March 24, 1924. Serial No. 701,249.

This invention relates to sewing machines and especially, although not exclusively, to multiple needle, locked chain-stitch sewing machines for operating upon relatively heavy work such, for example, as quilted materials.

The invention has for an object to provide stitch-forming mechanism in the form of a unit of such a character that any number of units adapted for simultaneous operation on the work may be readily included in a single machine and spaced as closely together as may be desired, said mechanism being of simple construction and capable of smooth operation at high speed by reason of the elimination of all cams and levers and the employment in lieu thereof of continuously rotating eccentrics or equivalent parts, it being understood that where the term "eccentric" is hereinafter employed it is intended to include any equivalent revolving part, such, for example, as a crank pin.

More particularly the invention contemplates the provision of improved stitch-forming mechanism comprising a needle motion wherein the needle is caused to partake of the feeding movement of the work while in engagement therewith, thereby permitting the employment of a continuous feed as is highly desirable when operating upon heavy work, in combination with looper mechanism including a looper and means for moving the same with the needle as the latter moves with the work, and also thereabout in the stitch-forming operation, the movements of said looper following a closed path in which the successive positions thereof are parallel, so that the spacing of the stitch-forming units is limited only by the thickness of the looper plus the necessary clearance.

The foregoing and other objects of the invention, together with means whereby the same may be carried into effect, will best be understood from the following description of one form or embodiment thereof illustrated in the accompanying drawings. It will be understood, however, that the particular mechanism described and shown has been chosen for illustrative purposes merely, and that the invention, as defined by the claims hereunto appended, may be otherwise practised without departure from its spirit and scope.

In said drawings:

Fig. 1 is a fragmentary longitudinal sec-

tion of a sewing machine having stitch-forming units embodying the invention, one of said units being shown in side elevation.

Fig. 2 is a front elevation of the looper mechanism, showing also the presser foot, the needle, and the lower ends of the needle and presser foot bars.

Fig. 3 is a section taken substantially on the line 3—3, Fig. 2.

Fig. 4 is an enlarged diagrammatic view of the seam formed by the machine as viewed from the under or looper side of the work.

Figs. 5, 6, and 7 are diagrammatic views illustrating the co-operation of the stitch-forming elements in the formation of the seam.

Fig. 8 is a diagrammatic plan view illustrating the movements of the looper.

The seam formed by the machine herein shown is diagrammatically illustrated in Fig. 4 as comprising an upper or needle thread A and a lower or looper thread B. The needle thread is passed through the needle holes C in the work W in a succession of loops a^1 , a^2 , a^3 , lying on the underside of the work, the intermediate portions d of said thread lying on the upper side of the work. The looper thread B is also formed in a succession of loops b^1 , b^2 , b^3 , lying entirely on the underside of the material and each of which extends through one of the loops of the needle thread A and about the next succeeding loop. Thus, for example, the loop b^2 of the looper thread B passes through the loop a^2 of the needle thread and about the loop a^3 of the latter thread, said loop a^3 passing through said loop b^2 .

Referring to Fig. 1, the frame of the machine is not shown in full but may be of any desired width and comprises a suitable number of transverse members, six of which are shown at 13, 14, 15, 16, 17, and 18, upon which the elements of the several stitch forming units are supported in their proper positions transversely of the machine. Each of said stitch-forming units comprises a needle 19, a presser foot 20 and a looper 21. In addition to the transverse frame members, the machine includes transverse shafts 22, 23, 24 and 25 adapted to receive power from any suitable source, not shown, and from which the several instrumentalities are operated, all of said shafts being continuously driven, and the shafts 23 and 24 having fixed thereon a pair of feed rollers 26 by

which the work W is fed continuously through the machine.

The upper stitch-forming instrumentalities of each unit are carried by a bracket 27 adjustably secured to the frame member 16, as by a bolt 28, while the lower stitch-forming elements are carried by a bracket 29 having a dovetailed engagement with the transverse frame member 18 and adjustably secured, as by a bolt 31, to the frame member 17 and carrying a work supporting or bed plate 32.

The presser foot 20 is carried by a presser foot bar 33 guided for vertical movement 15 in the bracket 27 and pressed against the work by a spring 34, said presser foot being manually raised by means of a cam lever 35.

The needle 19 is carried by a needle bar 36 vertically movable in a guide 37 pivoted 20 at 38 to the bracket 27. The needle thread A is supplied from a cop 39 carried by the transverse frame member 15, said thread passing through suitable guides 40 and 41 on the bars 14 and 15 to a tension device 42 25 carried by the needle bar 36 and thence through the eye of the needle to the work. The needle bar 36 has rigidly secured to its upper end an eccentric strap 43 surrounding an eccentric 44 on the shaft 22. The arrangement is such that the movement imparted to the needle bar by the eccentric 44 as indicated by the broken line n on Fig. 1, has a vertical component, causing the needle to penetrate and be withdrawn from the 30 work, and a horizontal component, causing the needle to be swung about the axis of the pivot 38 so as to follow the feeding movement of the work when in the latter. In other words the eye of the needle at its lower 35 end is caused to move in substantially an elliptical path into and out of the work, the major axis of this ellipse being substantially vertical. The tension device 42 enables the 40 needle bar to act as a take-up which tightens each stitch upon the upward movement 45 of the needle bar.

The looper thread B is supplied from a suitable source, not shown, and passes 50 through a tension device 45 on the frame member 13 and thence through a suitably disposed thread guide 46 and about a take-up 47 (hereinafter more fully described) to the looper 21. Said looper 21 is formed with a hook-shaped end provided with a 55 thread guide 48 (Figs. 5 to 7) and having at its end a perforation 49, the thread B passing from the guide 48 through the perforation 49 to the work.

The looper 21 is mounted in a carrier 50 60 in the form of a rocking slide carried by a rod 51 disposed parallel to the shaft 25 and supported at its ends in arms formed on the bracket 29, said slide being pivotally mounted on said rod to rock in a direction longitudinal of the machine, and having a limited

bodily movement in a direction longitudinal of said rod or transverse to the machine. The looper carrier 50 is rocked about the axis of the rod 51 by means of an eccentric 52 on the shaft 25, said eccentric being surrounded by a strap 53 having a stem 54 pivotally connected with said carrier by means of a pin 55 projecting from the latter. The take-up 47 is carried by the stem 54 so as to partake of the movements of the latter. The looper carrier is moved bodily on the rod 51 by means of an eccentric or crank pin 56 on a shaft 57 disposed perpendicular to the rod 51 and shaft 25 and journaled in a bearing 58 formed on the bracket 29, said eccentric or crank pin engaging a bearing block 8 which is received between a pair of spaced shoulders 60 formed on said carrier. The shafts 25 and 57 are connected by bevel gears 61, whereby the eccentrics 52 and 56 are inter-geared for rotation in unison, the angular positions of said eccentrics on their respective shafts being such that when the rocking movement of the looper by the eccentric 52 in either direction is at a maximum, the bodily movement thereof by the eccentric 56 will be at a minimum, and vice versa.

The formation of the stitch by the instrumentalities above described is illustrated 95 in Figs. 5 to 8. In Fig. 5 and at 1' in Fig. 8 the looper 21 is shown as rocked in its loop-taking movement into substantially its extreme forward position and also as moving bodily toward its extreme left position, as viewed from the front of the machine, and as shown in Figs. 2 and 3, the needle at this time being at substantially the upper limit of its movement. In this position the hooked end of said looper is shown as having 100 been passed through a loop a^2 of the needle thread A formed by a previous descent of the needle, carrying through said loop a^2 a loop b^2 of the looper thread B. The needle 105 19 then descends, as shown in Fig. 6, the looper 21 at the same time moving rearwardly at the left side of the needle to open or shed the loop b^2 , and said needle passing through both of the loops a^2 and b^2 . During 110 this operation the needle moves rearwardly 115 in the direction of feed, and the looper moves with it, the movement of the looper, however, being sufficiently in excess of that of the needle to cause the former to pass the latter. The looper 21 is then moved bodily 120 toward the right to the opposite side of the plane of the needle, causing the thread of the loop b^2 to be wrapped about the needle and about the needle loop a^2 so as to pass 125 the latter through the former, as indicated in Fig. 7. The needle then starts to rise, leaving behind it a second loop a^3 of needle thread, and the looper 21 is rocked forwardly at the right side of the needle, as shown 130 at 1' in Fig. 8, to pass a second loop b^3 of

looper thread through said loop a^3 . The needle then rises, and when the looper approaches substantially its foremost position, it is again moved bodily toward the left into the position shown in Figs. 2, 3 and 5, thus completing the cycle of operations. During the ascent of the needle and the forward rocking movement of the looper, the take-ups 42 and 47 operate to tighten the stitch.

10 The path of movement of the looper, as viewed in plan, is diagrammatically illustrated at l in Fig. 8, wherein n indicates the path of movement of the needle and n' and n^2 its forward and rearward limits of movement respectively. From this figure it will be seen that the looper moves, always in the direction indicated by the arrow and without reversal, in a closed, substantially elliptical path surrounding the path of movement of the needle.

15 20 The movement of the needle and that the successive positions assumed by the hook portion of said looper are all parallel to the direction of feed and consequently to each other. The ellipticity of this path depends upon the relative throws of the eccentrics 52 and 56, while the direction of its major axis depends upon the relative setting of the gears 61. These elements are so designed and relatively arranged that the longitudinal movements of the looper are sufficient to effect the loop shedding functions thereof and also to permit the same to pass laterally in front of the needle when the latter is in foremost position and laterally behind the needle when the latter is in its rearmost position, while its lateral movements are just sufficient to permit it to clear the needle on its longitudinal movements while passing as closely thereto as practicable.

25 30 35 40 45 50 55 The movements of the looper, produced by the eccentrics 52 and 56, are harmonic, and no reversal of movement is involved, so that the mechanism will run smoothly at high speeds. Since the looper is not turned or rotated on its axis, so that all of its positions are parallel, it will be seen that the needles and loopers of adjacent units may be set substantially as closely together as may be desired, the spacing of the needles being limited only by the thickness of the looper plus the necessary clearance. Finally, it will be seen that these results and advantages are secured by a very simple and inexpensive construction and arrangement of parts not subject to

disarrangement or requiring careful adjustment.

Having thus described my invention, I claim—

1. In a sewing machine, in combination, a needle, means for feeding the work substantially continuously independently of said needle, means for moving said needle toward and from the work to penetrate the latter and in the direction of feed to cause said needle to move with the work while in engagement therewith, a looper cooperating with said needle, and means for moving said looper without reversal in a closed substantially elliptical path surrounding the path of movement of the needle.

2. In a sewing machine, in combination, means for feeding the work, a needle, means for moving said needle toward and from the work to penetrate the latter and in the direction of feed to cause said needle to move with the work while in engagement therewith, a looper having a hooked end cooperating with said needle, and means for moving said looper in the direction of feed and also in a direction transverse thereto while maintaining said hooked end parallel to the direction of feed in all positions.

3. In a sewing machine, in combination, means for feeding the work, a needle, means for moving said needle in a substantially elliptical path to penetrate the work and move with the same while in engagement therewith, a looper having a hooked end cooperating with said needle, and means for moving said looper without reversal in a closed substantially elliptical path surrounding the path of movement of the needle while maintaining said hooked end parallel to the direction of feed in all positions.

4. In a sewing machine, in combination, a substantially straight needle, means including a pair of rolls for feeding the work substantially continuously independently of said needle, means for reciprocating said needle toward and from the work to penetrate the latter and for swinging the same in the direction of feed to cause said needle to move with the work while in engagement therewith, and means for moving said looper without reversal in a closed substantially elliptical path surrounding the path of movement of the needle.

In testimony whereof I affix my signature.
LEWIS F. FALES.
